FOLDING SCAFFOLD

Fredrich J. Gunther, Olive, Calif.

Application February 28, 1939, Serial No. 258,896

1 Claim. (Cl. 304—7)

This invention relates to scaffolds of the self sustaining type, and more particularly to a trestle which can be folded to facilitate transportation thereof, and which is adjustable as to height so as to adapt it to support work and/or workmen at different elevations.

An object of my invention is to provide a trestle of convenient and compact form, which, while being amply rugged to serve adequately as a carpenter's horse or work bench, or as a scaffold for painters, carpenters, lathers, plasterers, or substantially any type of workmen called upon to work in locations not conveniently reached from the floor or ground, and yet which is adapted to fold into compact form and is sufficiently light construction to be readily portable.

Another object is to provide a folding horse or trestle of the character described, the legs of which are extensible, so as to adapt it for the performance of work at several different elevations.

A further object of this invention is to provide a locking device of novel and highly efficient design, for releasably fastening the legs in selected degree of extension.

A still further object of my invention is to provide a folding and extensible horse or trestle of the general character indicated, which is of simple, rugged, and durable design, and which can be produced at low cost even in relatively small quantities, so as to adapt it for production and sale by a private individual and/or small organization without requiring the outlay of any large sum of money.

The invention possesses other objects and advantageous features, some of which, with those enumerated, will be set forth in the following description of the invention's particular embodiment which is illustrated in the drawing accompanying and forming a part of the specification.

The form of construction herein disclosed, has in actual use proven to be very efficient, amply rigid, capable of facile and rapid production, and generally desirable in other respects. For these reasons, the details herein disclosed may be considered as preferred. It should be mentioned, however, that while these details will hereinafter be specifically described, variations may be effected within the scope of the invention as claimed.

Referring to the drawing:

Figure 1 is a view in side elevation of a folding trestle incorporating the principles of the present invention.

Figure 2 is an end elevation, the direction of view being indicated by the arrow 2 of Fig. 1.

Figure 3 is an enlarged detail view in horizontal section, the plane of section being indicated by the line 3—3 of Fig. 2 with the direction of view as indicated by the arrows.

Figure 4 is an enlarged detail view in vertical section taken upon the line 4—4 of Fig. 3 with the direction of view as indicated.

Figure 5 is a perspective view of one end of the device, portions of the figure being broken away to reduce its size.

In its preferred embodiment, the folding scaffold of my invention comprises a horizontal top member 6, which may be conveniently formed of wood, as a board of suitable standard dimensions has been found to fulfill the requirements of the top member. Associated with each end of the top member 6 is a leg assembly 7, each pivotably connected adjacent its upper end to the top member in any convenient manner, as by a pin 8 extending through each leg 9 of the upper ladder 11 (which will be fully described hereinbelow) and through an angle bracket 12, one of which is provided adjacent each of the four corners of the top member 6 on its under surface. The pins 8 of each of the leg assemblies are axially aligned, so that each leg assembly can optionally be swung to top-supporting position, wherein it extends downwardly and outwardly from the top member 6, as illustrated in full lines in Fig. 1, or to folded or retracted position, closely underlying the top member 6, as illustrated in broken lines in that figure. Preferably the parts are so proportioned and arranged that when the leg assemblies 7 are folded, their lower ends are disposed closely adjacent each other, so as to make available the maximum length of supporting leg members for a given length of top member 6.

A flexible tension member, such as a length of cable 13, is attached at each end to one of the leg assemblies 7 at a point spaced from the associated pivot pins 8; and this cable is of such length that when stretched taut, it permits the leg assemblies to spread outwards slightly from the vertical, so as to add stability to the structure. A pair of compression members 14 are also provided, each comprising a brace pivoted at its lower end to one of the leg assemblies and adapted to be removably secured to the top member 6 as by a laterally extending finger 16 rigid with the brace at its upper end and receivable within an eye 17 on the under side of the top member 6 adjacent its center. A cotter pin 18, or its

equivalent, prevents accidental removal of each finger 16 from its associated eye.

This system of bracing, comprising the tension member 13 which prevents the legs from spreading, and the two compression braces 14 which support the center portion of the top member, has been found to impart such rigidity to the apparatus that the weight of several men can be supported upon the top member 6, even though it be constructed of a plank only one inch in thickness, without any appreciable flexure of the plank.

Each of the leg assemblies comprises an upper ladder member 11 and a lower ladder member 21 slidably mounted thereon in telescopic arrangement which permits adjustment of the leg assembly to that degree of extension appropriate to the particular work to be performed. Each of the upper ladder members 11 comprises a pair of legs 9 retained in spaced parallel arrangement by a plurality of horizontal steps 22; and each lower ladder member 21 is similarly comprised of legs 27 retained in spaced parallel arrangement by horizontal steps 24. The steps 24 of the lower ladder member are slightly longer than the steps 22 of the upper ladder member 11, with the result that the legs 23 of the lower ladder 21 receive the associated upper ladder member 21 therebetween where it is retained by being slidably engaged between the inner faces of the steps 24 of the lower ladder member 21 and brackets 26 rigid with the lower ladder member 21 and embracing the inner faces of the legs 9 of the upper ladder member 11 (see Figure 3).

Means are provided for releasably locking each of the leg assemblies in selected degree of extension. A rod 31 is carried by each lower ladder member 21, preferably adjacent the uppermost step 24 thereof. Each of these rods 31 is bent substantially to U-shape, the ends of the legs 32 of the U being pivoted to the legs 23 of the associated lower ladder and in axial alignment so that the portion 33 joining the legs can optionally be swung under any one of the steps 22 of the upper ladder member to retain the upper ladder in selected raised position with respect to the associated lower ladder, or withdrawn therefrom to permit telescoping of the upper ladder within the lower ladder. Instead of being straight, however, each leg 32 of each of the U-shaped rods comprises three sections angularly disposed with respect to each other. The substantially upright portion 36 is connected at its upper end with a laterally extending portion 37, which in turn is connected with an inwardly extending portion 38, to which the portion 33 of the rod is connected. The upright portion is pivoted at its lower end to the inner face of one of the legs 23 of the associated lower ladder 21, in position for the upright portion to engage the outer face of the associated leg 9 of the upper ladder 11; and the laterally extending portion 37 is of suitable length to offset the inwardly extending portion 38 far enough from the upright portion to extend inwards substantially parallel to the inner face of the associated leg 9 of the upper ladder 11.

Instead of engaging directly against the under face of a step 22, however, I prefer that this inwardly extending portion 38 of each of the rods 31 engage between spaced flanges 41 and 42 which extend inwards from suitable brackets 43, one of which is fastened under each end of each step 22 of each upper ladder 11. A third flange

44 on the upper end of each bracket 43 supports the associated end of the associated step 22.

By raising the upper ladder 11 of either of the leg assemblies 7 slightly higher with respect to the associated lower ladder than desired for any particular extension of that leg assembly, the inwardly extending portions 38 of the associated rod 33 can be interposed between the vertically spaced flanges 41 and 42 by two aligned brackets 43, with the result that when the upper ladder 10 11 subsequently slides downward upon its lower ladder, the upper flanges 42 bear against the inwardly extending portion 38 of the rod 33. This makes the upright portions 36 swing inward until they engage the outer faces of the legs 9 15 of the upper ladder 11, and when such engagement occurs, further swinging of the rod is prevented, with the result that the downward movement of the upper ladder is arrested.

Thus it may be seen that each leg assembly 20 can be adjusted independently of the other, to make it any desired length within the limits of its extensibility. Hence, one leg assembly can be made longer than the other to let it rest on the floor while the other rests on a step or some other support higher than that upon which the longer assembly rests, and still support the top member 6 in substantially horizontal position.

Preferably the rods 31 and the brackets 44 are of such design that the upper ladder is supported thereby with its steps 22 in alignment with the steps 24 of the associated lower ladder, as this facilitates the use of the leg assemblies as a means of access to the elevated top member 6. 35

I claim:

A folding trestle of the character described, comprising a horizontal top member, and a leg assembly pivotally secured adjacent each end thereof and adapted to be optionally moved to folded position underlying said top member or to top-supporting position extending angularly downwards and outwards therefrom, each of said leg assemblies comprising an upper ladder with which the pivotal connection for that assembly is associated, a lower ladder slidably mounted thereon for telescopic adjustment with respect thereto, and means for releasably locking said ladders in selected degree of extension comprising a rod bent to present at each end thereof an upright portion, an inwardly extending horizontal portion, and a laterally extending horizontal portion joining the upper end of said upright portion and the outer end of said inwardly extending portion, each of said upright portions being pivotally connected to one leg of one of said ladders and said pivotal connections of said upright portions being axially aligned, whereby said inwardly extending portions and the central portion of said rod joining them can be disposed under a step of the other ladder of the associated leg assembly with said upright portions engaging outer faces of one of said ladders to limit downward movement of said inwardly extending portions, and a bracket affixed to each leg of said other ladder under each of said steps thereof, each of said brackets comprising a plate affixed to the inner face of the associated leg, a flange projecting therefrom and supporting one end of one of said steps, and a pair of vertically spaced flanges spaced below said step-supporting flange and adapted to receive one of said inwardly extending portions of said rod therebetween. 65 70 75
